UNITED STATES PATENT OFFICE.

JOHN EVANS, OF SALT LAKE CITY, UTAH.

LAUNDRY-PIN RELEASER.

Application filed April 10, 1923. Serial No. 631,102.

To all whom it may concern:

Be it known that I, JOHN EVANS, a citizen of the United States, and a resident of Salt Lake City, in the county of Salt Lake,

5 State of Utah, have invented a certain new and useful Laundry-Pin Releaser, of which the following is a specification.

In modern commercial laundries there is now in general use a laundry assorting 10 reel which is provided with a series of rods that extend outwardly and downwardly from a common center, and the laundry articles belonging to each individual are identified by the use of ordinary safety 15 pins attached to each article and containing an identification mark. After the laundry has been washed, the articles are assorted by the operator placing upon a selected rod all of the laundry pins bearing a certain 20 identification mark, and these laundry pins attached to the laundry articles slide downwardly and outwardly on these rods and stand collected at the outer end of the rod. Considerable time and effort is required on 25 the part of the operator to individually release all of the safety pins by hand, and heretofore attempts have been made to provide means for simultaneously releasing a set of these safety pins at one operation. 30 These devices have not been successful so far as I am aware in solving the entire problem, because they attempt to release the pins by pulling upon the garments, which tends to tear the garments.

35 The object of my invention is to provide a device in the nature of an attachment that may be readily, quickly and easily applied to the frame of a laundry assorting reel of the class described, and when the 40 laundry pins with the laundry articles attached thereto stand collected at the lower end of the assorting rod, the operator may readily and easily examine, count and identify them, and then readily, quickly and easily 45 by the manipulation of a single lever release all of the safety pins, thus releasing the laundry articles so they may drop into the operator's arm, and at the same time having the pins all stand collected upon a 50 detachable pin holder, whereupon the assorting rod may be removed from the device and then the pin collector may be removed

and the pins collectively placed in a suitable receptacle without being individually handled by the operator at any stage of the 55 proceedings.

My invention consists in the construction, arrangement and combination of the various parts of the device, whereby the objects contemplated are attained, as hereinafter 60 more fully set forth, pointed out in my claims, and illustrated in the accompanying drawings, in which:

Figure 1 shows a top or plan view of a portion of an assorting reel frame with an 65 assorting rod therein, and my improved pin releasing device applied thereto. In this view there is shown a number of laundry pins in position within the releasing device.

Figure 2 shows an inverted plan view of 70 same. The dotted lines illustrate the movement of the releasing lever.

Figure 3 shows a transverse, sectional view taken through the central portion of 75 Figure 1, showing a laundry pin in position in the pin releasing device, and also showing the pin releasing device in position with the pin point removed from the pin point keeper.

Figure 4 shows a similar view with the 80 pin point in position within the pin point keeper.

Figure 5 shows an enlarged, detail sectional view taken on the line 5—5 of Figure 4, 85 and showing the laundry pin in position within the keeper and also showing by dotted lines the keeper moved to position for releasing the laundry pin from it.

Figure 6 shows a side elevation of a part 90 of the laundry pin releaser frame with a laundry assorting rod in its upwardly inclined position as in use, and also showing a series of laundry identifying pins on said rod with the laundry articles supported by 95 the pins. Said view also shows the laundry pin releasing device attached to the frame; and

Figure 7 shows a sectional view on the line 7—7 of Figure 1 with the pin collecting 100 device removed from the pin releasing frame, and shown in position slightly elevated above the pin releasing frame.

Referring to the accompanying drawings,

I have used the reference numeral 10 to indicate that portion shown of the laundry reel frame. These are usually made of hollow metal tubing and are substantially 5 circular in form. 11 indicates one of the laundry assorting rods, the lower end of which is usually supported in the frame member 10, and its body portion is extended upwardly and inwardly toward a common 10 center, and means not shown are provided for supporting the upper end of the rods.

The safety pins herein illustrated and described are of the form now in common use for laundry identifying purposes, and are 15 substantially the same in construction and mode of operation as the ordinary commercial safety pins, except that there is provided on each pin a metal plate at 12, which usually carries an identification mark. In 20 the drawings I have used the reference numeral 13 to indicate the pin point, 14 the pin body portion, and 15 the pin point keeper. In safety pins of this kind there is usually provided at the central portion of 25 the pin point keeper a guard plate 16, which extends from the body portion 14 toward the center of the pin point keeper, the inner end of which stands spaced apart from both sides of the keeper 15, as clearly shown in 30 Figure 5.

My improved device is in the nature of an attachment that may be readily, quickly and easily applied to any of the ordinary laundry assorting reels, and it comprises a 35 base 17 designed to be secured to the frame member 10 by bolts 18. Formed on this base 17 are two arms 19 and 20, which arms are spaced apart from each other, and the arm 19 is curved away from the arm 20 at its 40 upper inner end at 21. The arm 20 is provided with a corresponding curve at 22. The base 17 is formed with an opening through which the rod 11 may be extended into the frame member 10, as illustrated in Figure 2. 45 The arm 19 is provided on its face adjacent to the arm 20 with a downwardly extended flange 23, and the arm 20 is provided on its side adjacent to the arm 19 with a downwardly extended flange 24, the latter flange 50 being extended downwardly a short distance, as clearly shown in Figure 4.

These flanges 23 and 24 stand spaced apart from each other a distance slightly less than the distance between the pin point 13 and 55 the pin body 14 of the laundry assorting pins to be used with my device, and this means that when pins are placed upon the rod 11 and moved downwardly to position between the flanges 23 and 24, they cannot 60 extend at right angles to the arms, but must be inclined to about the angle shown in Figure 1, the purpose of which will hereinafter be made clear.

In the inner face of the arm 19 I have 65 formed a shoulder at 25 inclined down-

wardly and toward the frame member 10 and beveled on its face adjacent to the member 10, as clearly shown at 26 in Figure 1, and formed in the base 17 adjacent to the arm 19 is a notch 27, shown in Figures 1 and 70 7. This notch inclines downwardly and away from the frame member 10, and a limiting pin 28 is positioned adjacent to the lower end of the notch 27.

The pin collecting device comprises a 75 plate 29 having one end inclined and beveled at 30 to engage the shoulder 25, and its other end is inclined and beveled at 31 to fit in the notch 27 and be supported on the pin 28, and attached to one face of this plate 29 is 80 the pin collecting arm 32, which arm is secured to the plate 29 at its end adjacent to the frame 10, as shown in Figure 1, and it stands spaced apart from the plate 29 throughout the rest of its length. Its end 85 farthest from the base 17 is beveled or inclined, as shown at 33 in Figure 1, and its face farthest from the arm 19 is intended to lie flat against the adjacent side of the assorting rod 11, as shown in Figure 1. 90

Mounted adjacent to the inner face of the flange 23 is a laundry pin releasing bar 34 supported at both ends by a bolt 35 which is slidingly extended through the flange 23 so that the bar may move inwardly. On 95 each bolt there is a nut 36 and a spring 37. This spring's function is to engage the outer surface of the flange 23 and normally hold the bolt to its outer limit of movement, so that the pin releasing bar 34 normally stands in position resting against the flange 23, as shown in Figure 4, but may be moved inwardly to the position shown in Figure 3. 100

I preferably secure to the inner face of the pin releasing bar 34, a rubber strip 38 to engage the pin point keeper of safety pins to prevent the pins from slipping relative to the pin releasing bar. 105

For moving the pin releasing bar, I have provided a concaved lug 39 on the pin releasing bar 34, as shown in Figure 2, and I have mounted on the arm 19 a cam lever 40 having a limiting shoulder 41. This cam lever projects through the flange 23 and 110 normally engages the concaved lug 39. When this lever is in the position shown by solid lines in Figure 2, the pin releasing bar is held close to the flange 23, but when it is moved to its other limit of movement, as shown by dotted lines in Figure 2, then the pin releasing bar is at its limit of movement 115 away from the flange 23 and in the position shown in Figure 3. 120

It is desirable that all of the pins, when 125 they enter between the flanges 23 and 24, shall assume inclined positions all in the same direction relative to a line at right angles through the arms 19 and 20, as shown in Figure 1, and to accomplish this purpose I have provided on the curved face 21 of 130

the arm 19 a lug 42 to engage the part 14 of each pin as it moves to position between the arms 19 and 20, and this lug tends to retard the movement of the part 14 of the 5 safety pin.

On the opposite side and somewhat beyond the lug 42 I have formed a notch 43 in the curved portion of the arm 20, which notch tends to permit the part 13 of the pin 10 to readily swing toward the base 17, while the part 14 of the pin is being retarded. By this means all of the pins, as they enter between the arms 19 and 20, are tilted so they stand all at the same angle.

15 In practical use and assuming that the parts are properly assembled, then the operator places all of the laundry pins bearing the same identification mark upon one of the rods 11, and they will then slide 20 downwardly and outwardly by gravity until they reach the curved ends 21 and 22 of the arms 19 and 20, where they will stand assembled. While in this position the operator may readily and easily examine the pins 25 and thereby count and identify the laundry articles. When this has been done, the operator moves all of the pins by a single movement of her hand to position between the arms 19 and 20. Then the lever 40 is 30 manipulated, and all of the pins are simultaneously released.

The manner in which this releasing of the pin points is done is clearly illustrated in Figure 5, in which the pin is shown in section with the part 14 engaged by the pin releasing bar 34 with its rubber face 38 and the pin point 13 is engaged by the stationary flange 24. Obviously, when the pin releasing bar 34 is moved in a straight line at 40 right angles to the arm 20, it will move the pin point keeper to the position shown by dotted lines in Figure 5, and since the pin point 13 is held stationary during this movement, the pin point is released from the pin 45 point keeper, and when the lever 40 is returned to its starting position, the pin point will assume a position outside of the pin point keeper and the garments supported on these released pin points may then drop 50 by gravity or be pulled bodily from the free pin points.

To remove the pins from the pin collector, I first withdraw the rod 11 upwardly away from its position between the arms 19 and 55 20, and then grasp the pin collector 32 and bodily raise it and the plate 29 from its position between the arms 19 and 20 with all of the pins supported by it, and when this is done, the pins may be readily slid off of the 60 free end of the pin collector bar 32 into a suitable receptacle, and need not be individually handled. After the pins have thus been removed, the plate 29 is replaced and the rod 11 is replaced, and the device 65 is then ready for another operation.

I claim as my invention:

1. A pin releasing device comprising an assorting bar designed to receive a series of safety pins and to enter between the safety pin body members and point members, two 70 pin engaging members arranged on opposite sides of the bar, one being so positioned as to engage the bodies of the safety pins on the bar and the other to engage the pin point members thereof, and means for moving one of the pin engaging members toward and from the other for releasing the pin points from their keepers.

2. A pin releasing device comprising an assorting bar designed to receive a series of 80 safety pins and to enter between the safety pin body members and point members, two pin engaging members arranged on opposite sides of the bar, one being so positioned as to engage the bodies of the safety pins on the bar and the other to engage the pin point members thereof, and means for moving one of the pin engaging members toward and from the other for releasing the pin points from their keepers, the space between the 85 said pin engaging members being such that the safety pins on the bar upon entering between the pin engaging members must assume positions inclined relative to a line at right angles to the adjacent faces of the 90 pin engaging members, for the purposes stated.

3. A pin releasing device comprising an assorting bar designed to receive a series of 100 safety pins and to enter between the safety pin body members and point members, two pin engaging members arranged on opposite sides of the bar, one being so positioned as to engage the bodies of the safety pins on the bar and the other to engage the pin point 105 members thereof, means for moving one of the pin engaging members toward and from the other for releasing the pin points from their keepers, and a detachable pin collector blade adjacent to one side of the assorting 110 bar to enter the pins with the assorting bar.

4. A pin releasing device comprising an assorting bar designed to receive a series of safety pins and to enter between the safety pin body members and point members, two 115 pin engaging members arranged on opposite sides of the bar, one being so positioned as to engage the bodies of the safety pins on the bar and the other to engage the pin point members thereof, means for moving one of the pin engaging members toward and from the other for releasing the pin points from their keepers, and a detachable pin collector blade adjacent to one side of the assorting 120 bar to enter the pins with the assorting bar, said assorting bar being detachable relative to the pin collector blade.

5. A pin releasing device comprising an assorting bar designed to receive a series of 125 safety pins and to enter between the safety pin body members and point members, two pin engaging members arranged on opposite sides of the bar, one being so positioned as to engage the bodies of the safety pins on the bar and the other to engage the pin point members thereof, means for moving one of the pin engaging members toward and from the other for releasing the pin points from their keepers, and a detachable pin collector blade adjacent to one side of the assorting bar to enter the pins with the assorting bar, said assorting bar being detachable relative to the pin collector blade.

pin body members and point members, two pin engaging members arranged on opposite sides of the bar, one being so positioned as to engage the bodies of the safety pins on the 5 bar and the other to engage the pin point members thereof, and means for moving one of the pin engaging members toward and from the other for releasing the pin points from their keepers, one of the pin engaging 10 members being formed with a lug in the path of the pins on the assorting bar to tilt the pins as they enter between the pin engaging members.

6. A pin releasing device comprising an 15 assorting bar designed to receive a series of safety pins and to enter between the safety pin body members and point members, two pin engaging members arranged on opposite sides of the bar, one being so positioned as 20 to engage the bodies of the safety pins on the bar and the other to engage the pin point members thereof, and means for moving one of the pin engaging members toward and from the other for releasing the pin points 25 from their keepers, one of the pin engaging members being formed with a lug in the path of the pins on the assorting bar to tilt the pins as they enter between the pin engaging members and the opposite pin engaging member being formed with a notch to aid in said tilting movement.

7. A device of the class described comprising a frame member, two stationary arms fixed to the frame member and spaced 35 apart from each other, an assorting rod detachably mounted between said arms, and spaced apart from both arms, said rod being designed to receive safety pins and support them in position between the arms, and 40 a pin releasing bar slidably mounted on one of the arms below the assorting rod and being designed to engage the pin point keeper of the safety pins supported on the assorting rod, and means for moving said 45 releasing bar, for the purposes stated.

8. A device of the class described comprising a frame member, two stationary arms fixed to the frame member and spaced apart from each other, an assorting rod detachably mounted between said arms, and spaced apart from both arms, said rod being designed to receive safety pins and support them in position between the arms, and a pin releasing bar slidably mounted on one 50 of the arms below the assorting rod and being designed to engage the pin point keeper of the safety pins supported on the assorting rod, means for moving said releasing bar, and a rubber strip on the side of the releas-

ing bar that engages the safety pins, for the 60 purposes stated.

9. A device of the class described comprising a frame member, two stationary arms fixed to the frame member and spaced apart from each other, an assorting rod detachably 65 mounted between said arms and spaced apart from both arms, said rod being designed to receive safety pins and support them in position between the arms, and a pin releasing bar slidably mounted on one of the arms below the assorting rod and being designed to engage the pin point keeper of the safety pins supported on the assorting rod, and means for moving said releasing bar, said means comprising a concaved lug on the releasing bar, bolts fixed to the releasing bar and slidably supported by the arm, springs on said bolts to normally hold the releasing bar toward the arm by which it is supported, and a cam lever supported by said arm and designed to enter the concaved lug, said lever being formed with stop lugs, for 70 the purposes stated.

10. In a device of the class described, comprising a supporting frame, an assorting bar 85 detachably mounted in said frame, a pin collector detachably supported adjacent to one end of the assorting bar, and a series of pins designed to be slidably supported upon the assorting bar and also designed to slidably receive and be supported on the collector bar, said parts being so constructed and arranged that pins with garments attached thereto may be mounted upon the assorting bar and moved to position adjacent 90 to the frame, and the pins may be opened to release the garments and then the assorting bar may be removed, leaving the pins all supported by the collector bar, then the collector bar may be removed with the pins, 95 100 for the purposes stated.

11. A pin releasing device comprising an assorting bar designed to enter and support a safety pin, two safety pin engaging members on opposite sides of the assorting bar 105 designed to engage the side members of the safety pins supported on the bar, the space between said safety pin engaging members being such that the safety pin to enter between them must assume a position inclined relative to a line at right angles through the longitudinal axis of the supporting bar, and means for moving one of the safety pin 110 engaging members toward the other along a line at right angles to the longitudinal axis 115 of the safety pin supporting bar.

Des Moines, Iowa, March 30, 1923.

JOHN EVANS.
